ANIMAL PELT PROCESSING MACHINE

Harvey V. Palmer, R.F.D. 5, Box 430, McHenry, Ill., and Robert H. Palmer, 1728 W. Ainslie St., Chicago 40, Ill.

Filed June 30, 1958, Ser. No. 745,639

11 Claims. (Cl. 69—46)

This invention relates to the art of scraping animal pelts and more specifically to a novel device for mounting a pelt in relation to a scraping device which is positioned to move along the pelt.

A general object of the invention is to devise a novel fleshing apparatus which incorporates a support for mounting an inverted animal pelt, the device including a traverse guide which movably carries a fleshing tool having a blade reciprocating generally parallel to the direction of traverse of the tool.

A further object is to devise such apparatus in which the entire skin may be processed with minimum manipulation in a simple and efficient operation.

Another object of the invention is to devise a novel pelt support and guide for the fleshing tool which has a blade readily adjustable with respect to its angle of incidence to the pelt and which requires simple manual operation to engage and disengage the tool with respect to the pelt and move it along the pelt.

These and other objects of the invention will become readily apparent from the specification and the drawings, wherein:

Figure 1 is a plan view of the novel fleshing apparatus; Figure 2 is an enlarged cross-sectional view taken essentially on line 2—2 of Figure 1; and

Figure 3 is a fragmentary cross sectional view taken approximately on line 3—3 of Figure 2.

Describing the invention in detail, there is shown a frame or support structure generally indicated 1 which includes a pair of end members or standards 2 and 3 having bases 4 and 5 for mounting on an associated wall 6.

The standards 2 and 3 have outer end portions 7 and 8, respectively, to which is connected a traverse or guide bar 9 extending generally horizontally therebetween.

The bar 9 supports a carrier generally designated 10 for pivotal movement about the axis thereof and for longitudinal movement thereon. The carrier 10 comprises a sleeve portion 11 slidably and rotatably telescoped upon the bar 9. The sleeve portion 11 has a flange 12 extending outwardly therefrom generally tangentially to the bar 9 and provides a top mounting surface 13 on which is supported a mounting saddle 14 which is connected to the casing 15 of the power unit 16.

The saddle mounting pad 17 sits atop the surface 13 and is connected to flange 12 on an axis y transverse to the axis x of the traverse guide bar 9 whereby the power unit 16 is adjustable about the axis y of the bolt 18 which has a shank 19 extending through opening 20 in the mounting pad 17, the lower end of the shank 19 being threaded at 21 and screwed into a threaded opening 22 in flange 12 whereby the bolt 18 may be loosened by turning the head 23 to unseat it from the top side 24 of the pad 17 whereby the unit 16 may be pivoted to any desired position and locked in place by tightening the bolt.

It will be observed that the prime power unit 16 carried a fleshing blade 26 of the type shown and described in a copending U.S. application for patent in the name of

2

Robert H. Palmer entitled Means and Method for Fleshing Pelts, Serial No. 663,441.

The blade 26 has a leading curved portion 27 with a dull fleshing edge 28 and has a generally flat trailing portion 29 which connects by bolts 30 to a split mounting block 30' which is fastened preferably by the same bolts 30 to the reciprocating bolt or output member 31. It will be noted that inasmuch as the blade is fastened to the unit 16, that adjustment of the unit about the axes x and y disposes the blade in corresponding position although the blade is adjustable about the axis z (Fig. 3) about the output member 31 so that the curvature of the pocket 33 of the blade properly admits the periphery of the hide 34 which is mounted on the tapered pole 35 positioned generally parallel to the guide member 9.

The pole 35 has provided on its pointed end 36 a depression or aperture 37 which admits a spring-loaded pin 38 therein of a releasable holder, the pin 38 extending into a housing 39 and has an enlarged guide and positioning portion 40 which slidably and rotatably fits within the bore 41 in the housing in peripheral engagement with the surface 42. The pin 38 is urged outwardly by a spring 43 compressed between a base 44 in the housing and opposing side 45 of the portion 40. Outward displacement of pin 38 is limited by the turned flange 46 of the housing abutting the guide and positioning portion 40.

The base end 47 of the pole is provided with a pin 48 which fits into an aperture 49 in the transverse inner end wall 50 of the base holder 51. The pole which is preferably of wood or indentable plastic material is pierced by the sharp axially extending pins 52 on the wall 50 to secure the pole and base holder against relative rotation.

The base holder 51 has a pair of side walls 53, 54 which interconnect the inner end wall 50 with the outer end wall 55, the walls 53, 54 being interconnected by an intermediate wall 56 which with wall 55 is provided with coaxial apertures 57, 58 admitting a spindle or pin 60 which is secured to the member 3. Thus the pole and base holder are rotatable about an axis generally parallel to the bar 9.

The base holder 51 mounts on opposite sides thereof a pair of tension devices 61, 62 each of which is spring operated tending to draw the cables 63, 64 into their housings 65, 66 respectively. The outer end of cable 63 is secured to a spring clamp 66' which is adapted to grasp a paw 67 of the pelt and the cable 62 is connected to intermediate the ends of a whiffletree 68, which in turn has its ends connected to short cable lengths 69, 70, the outer ends of which are provided with clamps 69', 70'. The clamp 66' grasps the tail extremity 67 and the clamp 69' grasps the paw extremity 71 and clamp 70' grasps the paw extremity 72 of the pelt.

The tension devices snug the pelt onto the tapered pole, the pelt being inverted and drawn over the pointed end 74 of the pole so that it assumes generally the conical form of the pole. The base 47 is interlocked by the locking means 52 with the base holder 51 so that there is no relative rotation and the relationship of the cable clamping devices to the pelt is maintained so that as the pole and pelt are rotated the pelt does not slip around the pole. It will be understood that the radial extent of the units 61 and 62 is such that they clear the shaft or bar 9 as the pole is rotated.

It is, of course, understood that various changes and modifications may be made in the details of construction in the foregoing specifically described embodiment of the invention without departing from the spirit thereof and that the invention is to be regarded only as restricted by the scope of the appended claims.

What is claimed is:

1. In a fleshing machine, a support including a pair of

laterally spaced standards, a holder on each standard, a pelt mounting pole extending between said holders, means releasably mounting said pole on respective holders, said pole having a base abutting one of the holders, means releasably interlocking said base and one holder against relative rotation, a pair of tension devices mounted upon said one holder each including a spring loaded cable, a clamp on one of said cables for clamping one extremity of a pelt mounted upon the pole, a whiffletree connected to the other cable, and clamping means on the whiffletree for clamping the other extremities of the animal pelt, said one holder pivotal with the pole with respect to the associated standard.

2. In a pelt fleshing machine, the combination of a support, a pelt-mounting pole, means rotatably supporting the pole on said support, and means for snugging a pelt on the pole comprising a plurality of tension devices carried on said means and including means releasably connectible to the paws and tail of a pelt.

3. The invention according to claim 2 and interlocking means on said first-mentioned means and the pole for interlocking the same against relative rotation, said second-mentioned means when holding the pelt releasably urging said interlocking means into engagement.

4. In a pelt fleshing machine, a support, an elongated pelt pole mounted thereon, a traverse guide on the support generally parallel to the pole, a slide member pivoted on the guide on an axis generally parallel to the pole, a knife-driving unit adjustably mounted on the member for adjustment about an axis transverse to said last-mentioned axis, a said unit having a reciprocal output member, and a knife mounted on said member on an axis angularly related to said first and second mentioned axes, said blade extending at an acute angle to said pole and having a cutting edge proximate to the pole.

5. In a pelt fleshing machine, a support, a pelt pole mounted thereon, a traverse member on the support generally parallel to the pole, a mounting element slidably mounted on said member for movement thereon alongside the pole and pivotal movement toward and away with respect to the pole, a supported structure mounted upon said element on an axis transverse to said element, a cutting unit on the structure including an output member, and a cutting element mounted upon the output member and reciprocal thereby generally lengthwise of the pole, said cutting element adjustable about an axis angularly related to said axis and changing its presentation with reference to the pole and an associated pelt thereon.

6. A fleshing machine, comprising a support, a pelt pole mounted thereon, a traverse bar supported alongside the pole, and a cutting device on said bar movable toward and away with respect to the pole and alongside thereof, said device having parts relatively adjustable about an axis transverse to said bar and having a cutting blade disposed at an acute angle to said pole, and adjustable about an axis disposed at an acute angle to said pole, said blade

reciprocal at said angle to said pole and having a curved leading portion generally concentric to the pole.

7. A fleshing machine including a support structure having a pair of holders coaxially rotatably mounted thereon, a pole having a pointed end and a wide base end and having an aperture at said pointed end, one of said holders having a spring urged pin extending into the aperture, a plurality of pins on the other holder piercing the base end of the pole, a plurality of tension devices on the other holder for snugging a pelt upon the pole by drawing it from said pointed end toward the widened base end and holding the pole in engagement with the pins, and a cutting device mounted for translatory movement upon the support alongside of said pole and having a cutting element reciprocal toward the base of the pole.

8. A fleshing machine having a support, a pelt pole rotatably supported thereon, traverse means on the support alongside of said pole, a cutting tool mounted upon the traverse means for swingable movement toward the pole and traverse therealong, said tool including a blade reciprocal generally parallel to the pole at a slight acute angle toward one end of the pole, means releasably interlocking said pole with the support, and said interlocking means comprising a holder rotatably mounted on the support and pins on the holder extending in piercing relation to said pole.

9. A fleshing machine having a support, a pelt pole rotatably supported thereon, traverse means on the support alongside of said pole, a cutting tool mounted upon the traverse means for swingable movement toward the pole and traverse therealong, said tool including a blade reciprocal generally parallel to the pole at a slight acute angle toward one end of the pole, means releasably interlocking said pole with the support, and means including pins on said interlocking means engaging the pole and spring loaded cable means with clips for clamping the extremities of a pelt on the pole and drawing the interlocking means into engagement with the pole.

10. The combination of a support, a pole for mounting a pelt to be fleshed, means releasably mounting said pole on the support, and pelt holding means operatively connected to said means and operative to urge said pole into interlocking engagement with said means while holding an associated pelt upon said pole.

11. The invention according to claim 10 and said pelt holding means comprising tension means stretched between said first-mentioned means and the pelt, and said pole and first-mentioned means including axially telescoping parts held in engagement by said tension means.
